UNITED STATES PATENT OFFICE.

LEWIS CRAVEN ORD, OF MONTREAL, QUEBEC, CANADA, ASSIGNOR TO CANADIAN GOLD CAR HEATING & LIGHTING COMPANY, LIMITED, OF MONTREAL, CANADA, A CORPORATION OF CANADA.

MEANS FOR REGULATING STEAM-HEATING SYSTEMS.

1,108,218.

Specification of Letters Patent.

Patented Aug. 25, 1914.

Application filed August 3, 1910. Serial No. 575,381.

To all whom it may concern:

Be it known that I, LEWIS CRAVEN ORD, of the city of Montreal, Province of Quebec, Canada, have invented certain new and useful Improvements in Means for Regulating Steam-Heating Systems; and I do hereby declare that the following is a full, clear, and exact description of the same.

My invention has for its object to enable 10 the heat radiating properties to be regulated without varying the steam pressure.

The invention consists of a steam heating system regulator utilizing a variable overflow level of the water of condensation in 15 the heat radiator to vary the heat radiating surface and thereby regulate the radiating properties of the system.

For full comprehension, however, of my invention reference must be had to the accompanying drawings forming a part of 20 this specification, in which similar reference characters indicate the same parts and wherein—

Figure 1 is a side elevation of a railway car heater with my invention applied thereto; Fig. 2 is a plan view thereof; Fig. 3 is a detail longitudinal vertical sectional view of my improved regulator; Fig. 4 is a plan view thereof partly broken away; and Figs. 5 and 30 6 are transverse horizontal sectional views thereof taken respectively on lines A A and B B Fig. 3 looking in the direction of the arrows.

My improved regulator comprises a stand pipe *b* screwed at its lower end into a casting *c* the lower face of which forms a valve seat *c'* and having a pipe connection *d* to the lower end of the radiator, such pipe including a downwardly offset portion *e* forming 35 a water pocket acting as a steam trap. This casting *c* is connected by a union nut *g* to a valve casing *h* from which a waste pipe *i* leads to a thermostatic steam trap *j*, the upper end of the stand pipe being screwed into 40 a cap *k* from which a pipe *l* leads to the top of the radiator. A flat rotary valvular disk *m* is located within the upper portion of the casing and has a single segmental port *n* cut vertically therethrough, such valve being 45 operated by a valve shaft *o* extending upwardly through the stand pipe and cap *k* in the top of which latter it is rotatably held by a bonnet (to be presently described in detail) screwed therein, the upper portion of

the stem having a rigid collar *o'* and its upper end a handle *p* fixed thereon.

The valve seat has a series of preferably four ports *r s t u* arranged in a segmental series with which the valvular port *n* is adapted to coincide and open all the ports *r s t u* at the same time or any desired number of them. These ports serve as the discharge for the water of condensation and in order to afford means permitting constant flow during condensation and at the same time provide a series of different fixed discharge levels, a series of preferably three vertical tubes 2, 3 and 4 of different lengths are inserted into the upper ends of the ports *s t* and *u* respectively and soldered or otherwise fastened in place. The different angular positions of the valve are indicated by graduations 5 on the cap *k* and an indicator 6 formed by an extension 7 of the handle carrying a spring and ball, 8 and 9 respectively, coacting with indentations in the cap and corresponding with the graduations 5. The handle and valve are with this means set to secure the desired level of the water of condensation in the stand pipe and radiator. 80 A spring 10 keeps the valve *m* on its seat and between the spring and valve is located a cap 12 with a central pointed bearing teat 13 seated on a conical-bearing 14 on the underside of the valve. This cap prevents 85 twisting and wear of the spring when the valve is operated.

The bonnet before mentioned comprises a cylindrical portion 13^a screwed into a tapped opening in the cap *k* and formed with a circular recess 14^a in its underside to accommodate the collar *o'*, the upper end of the opening being enlarged as at 15 to receive a circumferential flange 16 formed on the bonnet and having a hexagonal upper face 95 to afford means for screwing the bonnet into place, the bonnet being seated by the underside of the flange resting upon the shoulder presented by the enlarged opening 15. A stuffing box is formed by a cylindrical projection from the upper end of the bonnet which encircles the shaft, the packing 18 being held in place by a bushing 19 and gland nut 20. To prevent unseating of the valve an annular boss 19^a is formed integrally 100 with the seat and extends upwardly encircling the stem proper 20^a of the valve and supporting a valve operating shaft *o* the

lower end whereof has a square recess receiving a square end of the valve stem. The upper end of the shaft is formed with a square end 22 projecting through a square opening 23 in the handle *p*, the collar *o* preventing the stem from being lifted. This particular construction and arrangement of the valve actuating mechanism precludes the possibility of the valve being depressed 10 from its seat or the shaft lifted from operative relation with the valve stem proper.

In the drawing my invention is illustrated applied to the heating of a water system, such for instance as is suitable for car heating, while the heating coil is indicated at 25, a water jacket for inclosing such heating coil at 26, flow and return steam pipes *d* and *b* respectively connecting as before stated the regulator to the heating coil, and flow and 20 return water pipes 27 and 28 respectively connecting the water jacket to the car heating pipes. Stops 40 and 41 limit the movement of the valve. The steam is supplied by pipe 30 branched as at 31 and 32 and 25 leading to the tops of the controller and heating coil 25 respectively, and the pipe *d* serves as the return connection from the heating coil to the controller.

Operation: The water of condensation 30 posited in the coil flows therefrom through pipe *d* into the bottom of the stand pipe above the valve seat *c*. When the controller handle is in position marked "Full" the port *r* is open and all water of 35 condensation flows from the trap *j* to waste. When the handle is in position marked "½" port *r* is closed and the water of condensation to escape must accumulate in the stand pipe and heating coil until 40 it reaches a level permitting it to overflow the tube 2, the radiating surface of the

heating coil being reduced in proportion; increased levels and corresponding decreased heating surfaces are obtained by turning the valve to close the tubes 2 or 3 in the latter 45 case the maximum water level and minimum heating surface are secured, but the stops 40 and 41 prevent the tube 4 being closed thus insuring a constant outlet for the water of condensation and preventing the blocking 50 of the radiator therewith. In this manner variations of the heating surface may be made, and as there is always a free discharge opening from the regulator the flow 55 of the surplus water of condensation after it reaches the required level is uninterrupted, and the free access at all times of either water of condensation or steam to the thermostatic trap, prevents freezing.

What I claim is as follows:—

The combination with a steam heating system and a heating coil therein, of a stand pipe connected to the heating coil and adapted to have the water of condensation escape therethrough, a conduit leading from 65 the heating coil to the stand pipe and having a downwardly offset portion providing a water pocket therein, means providing the stand pipe with a plurality of discharge openings arranged at different levels for the 70 water of condensation, and means whereby the water of condensation may be caused to collect in the said stand pipe and rise therein to any one of such discharge openings.

In testimony whereof, I have signed my 75 name to this specification, in the presence of two subscribing witnesses.

LEWIS CRAVEN ORD.
